UNITED STATES PATENT OFFICE

2,606,518

ANTIFOULING ANCHOR

Cleve F. Christie, Knoxville, Tenn., assignor of
ten per cent to Dove A. Harrison, Knoxville,
Tenn.

Application March 27, 1950, Serial No. 152,099

2 Claims. (Cl. 114—208)

1

The present invention relates to new and useful improvements in anchors and more particularly to means for releasing the anchor when engaged with submerged objects to prevent fouling of the anchor.

An important object of the invention is to provide means for releasing the flukes of the anchor, when fouled with a submerged object, by a twisting movement of the anchor rope.

Another object is to provide an interchangeable anchor releasing device which may be used with various types of anchors, such as a folding anchor or a rigid, non-folding anchor.

A further object is to provide an anti-fouling anchor of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the invention used with a folding anchor;

Figure 2 is an enlarged longitudinal sectional view taken on a line 2—2 of Figure 1;

Figure 3 is a longitudinal sectional view showing the flukes of the anchor released;

Figure 4 is a perspective view of the retrieving rods; and,

Figure 5 is a perspective view showing the invention used with a rigid, non-folding anchor.

Referring now to the drawings in detail, wherein for the purpose of illustration I have disclosed a preferred embodiment of my invention, the numeral 5 designates an anchor shank to one end of which an anchor lifting and lowering cable or chain 6 is attached by means of a ring 7.

The other end of shank 5 is formed with a threaded head 8 connected to an internally threaded socket 9. A semi-spherical body 10 is formed at the center of its rounded surface with a square stem 11 having a reduced threaded stud 12 threaded in the base of socket 9 and locked therein by a cotter pin 13. The flat surface of body 10 is formed with an eye 14.

A pair of wire or other suitable metal rods 15 are formed at each end with loops 16 and 17, loops 16 of the rods being swivelly secured to the opposite ends of a connector plate 18 having a central opening 19 for slidably mounting the connector on shank 5 with said rods 15 at opposite sides of

5 shank 5. In the form of the invention illustrated in Figures 1 to 3 inclusive, a substantially U-shaped anchor head is utilized as shown generally at 20 and which comprises a pair of flukes 21 rigidly connected to each other by a cross bar 22 having a substantially semi-spherical socket or recess at its center to separate cross bar 22 into a pair of aligned fluke arms 24 and 25, the socket being designated 23.

10 Semi-spherical body 10 is swivelly positioned in socket 23 with stem 11 swingable in a slot 26 in the bottom of the socket transverse to said bar 22 to permit arms 24, 25 to rotate about an axis transverse to the shank 5 and the flukes 21

15 to swing about said axis from one side of shank 5 to the other, or to swing into a folded position parallel to shank 5, the swinging movement of the flukes being limited by stops 27 at the ends of slot 26 and with which stem 11 engages when

20 said flukes 21 are swung from one side of said shank 5 to the other side thereof. Rods 15 are connected to arms 24 and 25, in other words, the cross bar 22 by the loops 17 in which said arms 24, 25, comprising the bar 22, are rotatable.

25 In the operation of the device, the flukes 21 swing downwardly below shank 5 when the anchor is lowered and anchor cable 6 holds the shank in an upwardly inclined position against one of the stops 27 to cause the flukes to dig into the bottom of the river or other body of water.

30 Should the flukes become fouled with a rock or other submerged object which prevents raising of the anchor, the anchor cable is then twisted in a direction to unscrew head 8 of shank 5 from socket 9 to release anchor head 20 from shank 5,

35 as shown in Figure 3, and connector plate 18 slides downwardly on shank 5 until it strikes head 8 and rods 15 then form a second lifting connecting means between shank 5 and anchor head 20 for freeing the fouled anchor. Cross bar 22 is

40 rotatable in the loops 17 so that flukes 21 may swing as previously described or into a position in longitudinal alignment with flukes 21 to subject the flukes to a straight rearward pull to free the anchor. As will be clear the head 8, socket 9, body 10, socket 23 and stem 11 form a threadedly connected coupling between the cross bar 22 and shank 5 uncoupled by twisting the cable 6.

45 The anti-fouling device may also be used with a rigid, non-folding type of anchor shown at 28 in Figure 5, by attaching eye 14 to the upper end of the rigid stem 29 of the anchor by a ring 30 whereby to form a swivel connection and attaching the loops 17 of rods 15 to the fluke arms 31 or cross bar of the anchor. The shank 5 is released by twisting the anchor cable in the same

manner as heretofore described and the fluke arms 31 or cross bar rotated in the loops 17 of rods 15 so that the flukes may swing from side-to-side of the shank 5 and also swing so that the rods 15 may exert a direct pull against the same when the stem 21 is uncoupled from the shank 5.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An anchor comprising a pair of flukes, a cross bar connecting said flukes, an anchor shank, an anchor lifting and lowering cable attached to one end of the shank, threadedly connected coupling devices between said cross bar and the other end of the shank uncoupled by twisting said cable to rotate the shank whereby to uncouple said shank from said bar when the flukes become fouled, means connecting said bar to one of said devices for rotation relative to the coupling devices when coupled to provide for swinging of said flukes in opposite directions about an axis transverse to said shank, and a second lifting means connecting said bar to said shank for

lifting said bar and flukes through lifting of said shank by said cable after uncoupling of said shank from said bar comprising a centrally apertured plate through which said shank extends and having limited lateral sliding movement on said shank, and a pair of rods upon opposite sides of said shank having corresponding ends swivelly connected to said plate and loops on the other ends thereof in which said bar is rotatable for swinging of said flukes.

2. An anchor according to claim 1, wherein said first-named means comprises a swivel providing for limited rotation of said bar and limited swinging of said flukes from one side of the shank to the other side thereof with said bar rotating in said loops, said swivel including a socket in said bar slotted transversely of the bar, and a ball member rotatable in said socket and having a stem swingable in said slot.

20 CLEVE F. CHRISTIE.
